CREDO HARRIS, OF LOUISVILLE, KENTUCKY, ASSIGNOR TO THE LOUISVILLE COURIER-JOURNAL COMPANY, OF LOUISVILLE, KENTUCKY.

REMOTE-CONTROLLED SIMULATED AND SIMULTANEOUS GAME.

Application filed December 14, 1925. Serial No. 75,484.

This invention relates to a remote controlled simulated and simultaneous game apparatus.

The chief object of the invention is to provide an arrangement or apparatus for duplicating a game such as a base-ball game, played at a distant point play by play by another team or teams through a central station connection with a transmitting device at the actual playing field, the receiving central station being located at or adjacent the simulated playing field.

The chief feature of the invention consists in the remote but simultaneous control of a team or teams upon a playing field substantially the duplicate of the original or actual playing field, the team or teams thereon representing the team or teams actually playing, the said representing teams being individually controlled from a central station play by play.

The full nature of the invention will be understood from the accompanying drawings and the following specification and claims:

In the drawings Fig. 1 is a diagrammatic plan view of a pair of playing fields with the several stations thereon and the players likewise suitably indicated and the means connecting one field to the other for securing simulated play upon one field, play by play, as the same is obtained on the actual playing field. Fig. 2 is a central sectional view of a portion of the playing field showing a part of the apparatus in section and other parts in elevation. Fig. 3 is an elevational view of one of the team players provided with the necessary equipment.

In the drawings, Fig. 1, indicates an actual playing field and a simulated playing field. These fields are herein shown as diamonds and the game played and simulated is base-ball, although the generic idea of the invention is not necessarily to be considered restricted to the playing of this particular game nor playing on particular fields of this particular type. The actual playing field in a base-ball game consists in four bases, first, second, third and home, forming a diamond, and within the diamond and approximately the center thereof is the pitcher's box or mound. Immediately back of the home plate is the catcher's box and between the home plate and the first base and home plate and third base two stations

are provided which are known as the coaching boxes. Also on each playing field there is generally a dug out or bench for the players. In addition to the before mentioned stations three additional stations are provided in the out field in the present game known as right, left and center fields. Also in addition to the four stations on the bases there is included the shortstop station, and generally in playing base-ball two governing officials are used and one who controls decisions on delivery and upon plays made at the home plate and the other who controls decisions on the bases and in the fields. Usually the first umpire's position is back of the catcher and the second umpire's position is back of the pitcher or between the pitcher and the second base. In the simulated playing field each of the before mentioned stations is provided with suitable means for simultaneously supplying information to a player or individual located at said station. In the present invention, however, the batter's box at the home plate is provided with two stations, one for right hand batters and the other for left-handed batters.

The actual playing field has a transmitter or transmitting device 10 that is adapted to convey messages to a central station 11 at the simulated playing field. This central station may be in communication with the transmitting station 10 either through mechanical connection such as telegraph and telephone lines, or through electrical connections of the wireless telephony type, or by a combination thereof, the last having been found most desirable. Thus plays announced into the transmitter 10 by an observer describing the same as they occur, play by play, on the actual playing field, will be transmitted to the central station 11, which central station 11 is in direct communication with all of the local stations on the simulating playing field through suitable circuits. Herein one conventional form is illustrated which shows a plurality of supply lines 12 which go to each of the stations and each of the stations is grounded as at 13.

Each station comprises a pair of insulating mats 14 and embedded therein but exposed thereon is a contact plate 15 in the form of a brass sheet. The two plates 14 are flexibly united and are suitably an-

chored to the playing field at the proper location. One of the plates 15 is electrically connected with the supply line 12, while the other plate is grounded as at 13 or a return line 13 may be employed which forms a return to the common source of energy conventionally illustrated by the battery 16.

The players take their proper positions and as the various plays occur the simulating players perform said plays as they actually occur on the playing field and as described by the observer at the transmitting station 10.

Each of the players is equipped with a belt 16 having thereon at least two metal strips 16^a, each of said strips having attached thereto two binding posts or contacts 17, one pair being connected by lines 18 to head phones 19 carried by each player, and the other pair of lines 20 to the contacts 21 secured to the shoes 22 of the player. The head phones 19 may be directly connected to the contacts 21 if desired. Thus when the player takes his position at each station he stands upon the mats 14 and thus establishes an electrical connection between the

head phones 19, which he carries, and the central station 11. Therefore all of the players are simultaneously in connection with the central station so long as they maintain their contact, and can play a simulated play by play game with or without the assistance of a ball.

The invention claim is:

The combination of a game playing field having stations thereon corresponding to the actual playing field and stations and a central station device for receiving from the actual playing field play by play directions corresponding to the actual play occurring thereon, and a suitable number of individual player reception devices carried by the simulating players, and means located at each of the simulating field stations detachably connecting the reception devices to the central station, whereby the individual players are in direct communication with said central station.

In witness whereof, I have hereunto affixed my signature.

CREDO HARRIS.
